Attys.

My invention relates to baptismal fonts and more particularly to baptismal fonts having a lock operatively associated therewith.

UNITED STATES PATENT OFFICE

BRUNO RICCINI, OF CHICAGO, ILLINOIS, ASSIGNOR TO DAPRATO STAUTARY COMPANY, OF CHICAGO, ILLINOIS, A CORPORATION OF ILLINOIS

LOCK

Application filed March 20, 1931. Serial No. 524,033. Prior art cited

This invention relates to a lock is particularly well suited for use on a baptismal font or similar enclosure. Baptismal fonts are customarily formed of marble or similar stone and consequently are quite heavy and difficult to lock in closed position.

It has been the practice heretofore to attach a hasp and keeper to the font and to use a padlock for locking the cover to the bowl portion. Such an arrangement is, however, unsightly and not in keeping with the rest of the fixture.

It is the purpose of this invention therefore to provide a neat decorative lock which is especially adapted for use on baptismal fonts and will not detract from the appearance of the font.

In receptacles of this type, particularly when formed of marble or other stone, difficulties are encountered in attaching parts such as locks thereto. It is desirable, therefore, that the lock may be secured or attached with a minimum amount of labor involved and with a minimum amount of drilling and preparation of the receptacle. It is also the purpose of this invention, therefore, to provide a lock which may be incorporated into a baptismal font with a minimum amount of labor and prior preparation of the font.

Other novel features and their resultant advantages will be apparent from the following description given in connection with the drawing in which:

Fig. 1 is a front elevation of a typical baptismal font having a lock operatively associated therewith in accordance with this invention.

Fig. 2 is a vertical section through approximately the center of the bowl and cover portions of the font.

Fig. 3 is a longitudinal section through approximately the center of the locking mechanism.

Referring more particularly to the draw-

ing, there is shown for purposes of illustration a conventional baptismal font comprising a base 1, pedestal 2, bowl 3 and cover 4. The cover 4 is hinged at the rear by a pintel 6. It will be manifest that the font shown is for illustrative purposes only and that any other type of font or similar receptacle may be employed.

The lower front edge of the bowl 3 is recessed as at 7 to receive the projecting end 55 of a latch member 8, pivoted at 9 between parallel flanges 11 formed upon latch plate 12. Plate 12 is secured within a recess formed in the lid of the font in any suitable manner. The pivoted latch member 8 is actuated by a lever 13 also pivoted intermediate its ends as at 14 to the flanges 11. The inner end of lever 13 engages the forked end 16 of latch member 8 to rotate the latter about its pivot into latched or unlatched position.

Lever 13 is actuated by a locking mechanism secured to the cover 4 which is provided with a single aperture for this purpose. The locking mechanism is enclosed within a cylindrical casing or shell 17 which terminates into a handle portion 18 which may be formed in any desired ornamental shape. The casing is bored internally throughout and threaded at the inner end 75 to receive an inner sleeve 19, the latter being threaded externally to engage the threaded end of the casing and to receive a nut 21. The cover of the receptacle can, therefore, be clamped between the shoulder 80 of the handle and the nut 21.

Slidely mounted within the ball of the handle is a reciprocatory lock cylinder 22 arranged to project through and extend beyond the handle when in unlocked position 85 as illustrated in Fig. 3. The distance which the lock cylinder projects is determined by engagement of collar 23 thereon with shoulder 24 formed in the bore of the casing by the wear collar 25 set therein. The lock 90

cylinder also carries a tumbler 26 which, when extended, engages shoulder 24 to prevent outward movement of the lock cylinder, thus maintaining the cylinder in locked position. It is understood that the tumbler is retractable by the insertion and turning of a key in the usual manner.

In order to normally maintain the lock in open position a coiled compression spring 10 27 is placed under compression between the inner end of collar 23 and the end of inner sleeve 19, the latter of which has a skirt portion 28 which houses the spring and limits inward movement of cylinder 22 by engagement with collar 23.

The actuating lever 13 is connected to collar 23 in order to be operated by cylinder 22 through the medium of a flexible rod 29 having one end secured to the collar and the other to the projecting end of lever 13.

It follows from the above that the outer tubular sleeve or casing 18 not only houses the entire locking mechanism but has as an integral part thereof an operating handle by means of which the font lid may be moved into open or closed position. When it is desired to lock the font, it is only necessary to push cylinder 22 inwardly, until tumbler 26 passes shoulder 24 and engages the same to prevent outward movement of the lock cylinder or plunger. In order to unlock the font, it is only necessary to insert and turn the proper key, upon which the tumbler 26 will be withdrawn and spring 27 will force lock 22 outwardly, thus swinging latch member 8 about its pivotal point into unlatched position.

It is obvious that minor changes may be made in the details of construction without departing from the spirit and scope of this invention as defined in the claims appended hereto.

I claim:

45. 1. In a locking mechanism, a cylindrical casing terminating at one end in an operating knob, a lock cylinder slidably mounted in said casing, means for limiting the sliding movement of said cylinder in both directions comprising a collar upon said cylinder and a sleeve within said casing, a spring within said casing for maintaining the cylinder in one extreme position, and means for locking the cylinder in its other extreme position and a latch actuated by said cylinder.

2. A lock mechanism comprising a cylindrical casing terminating in a knob, a lock cylinder slidably mounted in said casing and arranged to project from the knob when in unlocked position, means for locking said cylinder in closed position, a pivoted latch removed from said cylinder, and actuating means between said latch and said cylinder whereby said latch will be moved

about its pivot upon movement of said cylinder.

3. In a locking mechanism, a cylindrical casing terminating at one end in an operating knob, a lock cylinder slidably mounted in said casing, means for limiting the sliding movement of said cylinder in both directions, a spring within said casing for maintaining the cylinder in one extreme position, means for locking the cylinder in its other extreme position, and a latch actuated by said cylinder. 70 75

In witness of the foregoing I affix my signature.
